UNITED STATES PATENT OFFICE.

FRANS O. ALBERTSON, OF SIOUX CITY, IOWA, ASSIGNOR TO ALBERTSON & COMPANY, OF SIOUX CITY, IOWA, A CORPORATION OF IOWA.

REFACING-TOOL FOR PUPPET-VALVES.

1,285,573.

Specification of Letters Patent. Patented Nov. 26, 1918.

Application filed March 21, 1917. Serial No. 156,253.

To all whom it may concern:

Be it known that I, FRANS O. ALBERTSON, a subject of the King of Sweden, residing at Sioux City, in the county of Woodbury and 5 State of Iowa, have invented a certain new and useful Improvement in Refacing-Tools for Puppet-Valves, of which the following is a full, clear, concise, and exact description, reference being had to the accompanying drawings, forming a part of this specification.

My invention relates to devices for refacing valves; particularly puppet valves, such as are used in connection with internal combustion engines and broadly stated the object of my invention is to provide a cheap, efficient, simple and generally improved device of this character.

The specific embodiment of my invention 20 hereinafter described and claimed is in the nature of an improvement upon the device shown and described in United States Patent No. 1,087,625, granted to me on February 17, 1914. The most salient differences 25 between the device to which my present invention is directed and that shown and described in my aforesaid patent reside in the arrangement for rotating the valve, the means for retaining the face of the valve 30 against the cutting blade during the refacing operation, and in the arrangement of parts whereby the means last mentioned may readily be swung out of its operative position when a valve is to be placed in or re- 35 moved from the tool and is readily secured in operative position when a valve is to be subjected to the refacing operation.

The details of my improved tool as well as 40 the advantages afforded thereby will be set forth in the description to follow, wherein reference is made to the accompanying drawings.

Figure 1 is a side elevational view of my 45 improved tool with a valve placed therein ready to undergo the refacing operation;

Fig. 2 is an elevational view of one end of the device illustrating how the device is capable of being clamped and held between the jaws of a vise;

50 Fig. 3 is an elevational view of the opposite end of the tool;

Fig. 4 is a view generally similar to Fig. 3, but showing the movable bracket and screw carried thereby swung out of alignment with the valve carrying elements; 55

Fig. 5 is a fragmentary sectional view taken on the line 5—5 of Fig. 3, with the valve removed, and

Fig. 6 is a vertical sectional view taken on the line 6—6 of Fig. 5. 60

Similar characters of reference refer to similar parts throughout the several views.

Referring more particularly to Figs. 1 and 2, it will be noted that the device in question comprises a base in the form of a 65 casting 10. This base or support is so conformed that it may be clamped between the jaws of a vise 11 when the refacing device is in use. However, it is not essential that the base of the refacing tool be clamped in a vise 70 when a valve is undergoing the refacing operation, because due to the improvements which characterize my present invention the operator need employ but one hand in rotating the valve, thus leaving the other hand 75 free to hold the device stationary while the valve and its stem are being turned during the refacing operation.

Disposed at one end of the base or support 10 is a vertical bracket 12 conveniently formed integral with the base as shown. Also formed integral with the base intermediate the ends of the latter is a bracket 13 disposed parallel with the bracket 12, but of considerably less height than the latter. 80

Disposed upon the intermediate bracket 13 and conveniently secured thereto by a plurality of screws 14—14, one of which is most clearly shown in Fig. 5, is a bracket section 85

15, the upper edge of which lies in substantially the same horizontal plane as the upper edge of the fixed end-bracket 12. Formed in the upper edge of the fixed end-bracket 12 is a V shaped notch 16, and formed in the intermediate bracket section 15 is a corre- 90

sponding V shaped notch 17, which is alined with the first mentioned notch 16. As will 95 presently be explained, these notches 16 and 17 constitute a cradle wherein may be placed the stem of a valve, the head of which is to be subjected to the refacing operation. Asso-

ciated with the fixed end-bracket 12 and the 100

intermediate bracket section 15 are cross bars 18 and 19 respectively. Said cross bars serve to prevent a displacement of a valve stem resting in the notches 16 and 17 and are 5 retained in position by the thumb screws 20 and 21 respectively.

Formed integral with the intermediate bracket section 15 and projecting horizontally therefrom in a direction away from the 10 fixed end-bracket 12, is a boss 22 having a cylindrical surface of slightly more than 180 degrees. It will be noted that the V shaped notch which is formed in the intermediate bracket section 15 extends through the boss 15 22, as is most clearly illustrated in Fig. 5. Disposed upon the boss 22 is a collar 23 conveniently hexagonal in shape and provided 20 with a beveled inner surface 24. Secured in a notch formed in the collar 23 is a truing 25 blade 24' conveniently retained in position by a machine screw 25 extending through the collar and having its head countersunk therein, as shown most clearly in Fig. 5. The cutting edge 26 of the blade 24' is inclined to 30 correspond with the inclination of the bevel of the valve to be refaced thereby. In the present instance the cutting edge is illustrated as having an inclination of forty-five degrees to the axis of the valve when the latter is placed in the tool.

In my former patent I have illustrated how the blade carrying collar may be provided with a plurality of blades and how the collar may be adjusted to bring any one of 35 the said blades into operative position. In the present instance I have illustrated the blade carrying collar 23 as provided with but a single blade and fixed with respect to the boss 22 by a screw illustrated in dotted 40 lines at 27 in Fig. 6. In the present instance, therefore, the blade carrying collar is not adjustable, but it will be understood that the same may be made adjustable and provided with a plurality of cutting blades 45 if desired.

Disposed at that end of the base 10 opposite the fixed end bracket 12 is a swinging bracket 28, one leg of which is pivoted to the base 10 by a screw 29 extending freely 50 through an aperture in the swinging bracket and engaging in the base. The other leg of the swinging bracket is provided with an elongated slot 30 struck on an axis substantially concentric with the axis of the pivot screw 29, the said slot being arranged to cooperate, as shown in Fig. 3, with a thumb screw 31 carried by the base 10. Carried by the swinging bracket 28 and extending therethrough is a comparatively long thumb 55 screw 32, the threaded end of which is designed to engage the head of a valve when the same is to undergo the refacing operation.

In utilizing my improved device for the

purpose of refacing a valve head the thumb 65 screw 31 is loosened and the swinging bracket moved to the position illustrated in Fig. 4. With the swinging bracket in this position the stem of the valve to be refaced may be placed in the device, as shown in 70 Fig. 1, with the stem of the valve resting in the alined notches 16 and 17 formed in the end-bracket 12 and intermediate bracket section 15. The thumb screws 20—20 and 21—21 are then tightened down sufficiently to 75 retain the valve stem within the notches. It will thus be seen that the notches 16 and 17 constitute in effect a cradle adapted to receive valve stems of various diameters and that a valve when placed in said cradle lies 80 with its axis at an angle of substantially forty-five degrees with the cutting edge of the blade 24. After placing the valve in the device as just explained, the swinging bracket 28 is moved to the position illustrated in Fig. 3, and the screw 31 is tightened to retain the swinging bracket in operative position. The thumb screw 32 is then tightened up to cause the beveled surface of the valve head to engage the cutting 85 edge of the blade 24, as is most clearly illustrated in Fig. 1. It will be noted that the base 10 is of such length that an ordinary valve stem extends for a considerable distance beyond the fixed end-bracket 12 when 90 the valve is placed in the device. To this projecting end of the valve stem I apply a crank 33, the stem engaging arm of which is provided with an aperture of sufficient diameter to receive valve stems of various 95 sizes. The crank is secured upon the valve stem by a suitable set screw illustrated at 34. To reface the valve head the crank 33 is rotated and the screw 32 tightened up from time to time in order to keep the beveled 100 surface of the valve head in engagement with the cutting edge of the blade 24. After the refacing operation has been completed the screws 20, 21, 31 and 34 are loosened, 105 the crank removed from the valve stem and the swinging bracket moved to the position shown in Fig. 4, whereupon the valve may be removed from the refacing tool.

It will thus be seen that I have provided a compact and efficient device for refacing 110 puppet valves and that in order to rotate the valve I apply the necessary power to the valve stem by means of a crank secured thereto. The device is capable of being used for refacing puppet valves of various kinds 115 and sizes and the refacing operation may be carried on efficiently and rapidly.

Having thus described my invention, what I claim as new and desire to secure by Letters Patent of the United States, is:

A valve-grinding tool comprising a base 120 provided with an upward-extending boss forming a support for the stem of a valve,

and provided with a lateral extension, a collar secured upon said extension, a truing blade, secured to said collar and projecting from one side thereof, to engage the periphery of the head of a valve to be ground, and means for rotating the valve head relative to said blade and in contact therewith.

In witness whereof, I hereunto subscribe my name this 17th day of March, A. D., 1917.

FRANS O. ALBERTSON.
